(57) **CLAIM**

We claim the ornamental design for a delivery pod for autonomous vehicle, as shown and described.

DESCRIPTION

FIG. 1 is a perspective view of a delivery pod for autonomous vehicle showing our new, original, and ornamental design in a closed configuration;

FIG. 2 is a top view thereof;

FIG. 3 is a right side view thereof;

FIG. 4 is a front view thereof; and,

FIG. 5 is a perspective view thereof, shown in an open configuration.
